EDUCATIONAL TOY PUZZLE

Silas M. Ford, St. Paul, Minn.

Application January 10, 1952, Serial No. 265,788

6 Claims. (Cl. 35—39)

1

This invention relates to an improvement in educational toys and deals particularly with a puzzle of the jig-saw type which incorporates a compass.

Jig-saw puzzles have been found advantageous from an educational standpoint for educating young children. The child is taught to assemble the various parts in a predetermined relation and also to associate various colors and parts with a particular location. The present invention deals with a puzzle having a compass embodied therein so that the child may learn the operation of a compass and the manner in which the compass is used. The pieces forming the puzzle comprise the points of the compass and the child is taught the relationship of these points with respect to each other and with respect to the compass.

A feature of the present invention lies in the provision of a puzzle which includes a series of pieces which fit together in one particular relation. As a result the pieces of the puzzle which bear indicia indicating points of the compass are always in proper relation when the puzzle is assembled.

A feature of the present invention lies in mounting a compass in a center portion of the puzzle and in surrounding this center piece with puzzle parts which form the various points of the compass. The points are placed in predetermined relation relative to the center piece and with each other.

A further feature of the present invention resides in the provision of a puzzle which embodies a compass and removable parts which indicate the various points of the compass and in coloring the various puzzle pieces in such a way that the location of the pieces may be learned from association with color, as well as with a particular shape. As a result the puzzle is instructive in indicating various colors and in distinguishing one color from another.

These and other objects and novel features of my invention will be more clearly and fully set forth in the following specification and claims.

In the drawings forming a part of my specification:

Figure 1 is a top plan view of the puzzle showing the relationship of the parts therein.

Figure 2 is a sectional view through the puzzle, the position of the section being indicated by the line 2—2 of Figure 1.

The puzzle is indicated in general by the letter A. The puzzle preferably includes a base board 10 which may be of any preferred shape. This board being indicated as rectangular in the drawings. A covering panel 11 overlies the panel 10. The puzzle pieces are ordinarily a part of the panel 11 and are cut therefrom prior to the as-

2

sembly of the device. For the purpose of simplicity the numeral 11 will designate the frame of the puzzle. This frame 11 is adhered or otherwise secured to the base panel 10 and is usually of the same outline shape. When the frame 11 is adhered to the base panel 10, a recess is formed into which the various puzzle pieces may be inserted.

The puzzle itself is provided with a center piece 13 having a circular aperture extending therethrough. The aperture 14 is designed to accommodate a compass which is indicated in general by the numeral 15. In the particular form of construction illustrated the compass 15 is enclosed in a transparent casing which includes a bottom disc 16 and a cup shaped cover piece which includes a circular cover panel 17 having cylindrical side walls 19 connected thereto. The end of the side wall 19 is provided with a peripheral flange 18. The disc 16 is pressed into the side wall 19 to extend flush with the flange 18. Suitable cement or adhesive is usually used between these parts to seal the interior of the housing formed in this manner.

The disc 16 is provided with a support 20 and a pivot or spindle 21. The magnetic needle 22 supports a center bearing 23 which is loosely supported upon the spindle 21 so as to rotate freely. The bearing 23 usually extends into close proximity with the cover panel 17 of the enclosure 15 so that the needle cannot move longitudinally upon the spindle 21 a distance sufficient to permit disengagement thereof.

The compass enclosure 15 is frictionally engaged in the aperture 14 of the center piece 13 and may be held in place by adhesive if desired. A groove is usually formed in the center piece 13 encircling the aperture 14, this groove being indicated at 24 for accommodating the flange 20 of the enclosure so that the outer surface of the disc 16 and flange 20 may extend flush with the surface of the puzzle piece 13.

A pointed puzzle piece 25 adjoins the center piece 13 and is separated therefrom by an irregular line 28 so that this piece 25 will fit only in one relative position with respect to the center piece 13. A second pointed piece 27 likewise is separated from the center piece 13 along the irregular line 26 so that this piece 27 must be located opposite the piece 25. Two additional pointed pieces 29 and 30 are arranged on opposite sides of the center puzzle piece 13, these pieces also being separated from the central piece along the irregular line 26 so that they can fit in one relative position only.

It will be noted that the pointed pieces thus described extend beyond a circular outline 31 so that the proper location of these pointed pieces

relative to the frame 11 is insured. The pointed notch 32 at the upper end of the circle accommodates the pointed piece 25. A somewhat similar notch 33 extends into the frame 11 in diametrically opposed relation to the notch 32. The notch 32 is somewhat larger than the notch 33 so that the puzzle piece 25 may fit properly only in one position in the frame.

Opposed notches 34 and 35 extend into the frame 11 on opposite sides of the circular outline 31. These notches are designed to accommodate the pointed ends of the puzzle pieces 29 and 30.

A puzzle piece 36 having a double point 37 extends into a notch 39 in the frame 11. This puzzle piece 36 is provided with a rounded end 40 which fits a similar contour in the pointed puzzle pieces 25 and 29 at the juncture thereof. A somewhat similar puzzle piece 41 also having a double point 42 extends into a notch 43 which is diametrically opposed from the notch 39. However, the end of the puzzle piece 41 opposite the pointed end thereof is in itself pointed as indicated at 44, as distinguished from the rounded end of the puzzle piece 36. Thus the puzzle pieces 36 and 41 cannot be substituted one for the other in the assembly of the puzzle.

A puzzle piece 45 having a rounded outer end 46 and a rounded inner end 47 extends into a rounded notch 49 in the frame 11 and into a rounded recess at the juncture between the puzzle pieces 25 and 30. A somewhat similar puzzle piece 50 having a rounded outer end 51 fits into a rounded notch 52 in the frame 11. This notch 52 is diametrically opposed to the notch 49. The puzzle piece 50 differs from the puzzle piece 45 in having a pointed end 53 which fits into a similarly shaped part of the adjoining surfaces of the puzzle pieces 27 and 29.

The puzzle also includes puzzle pieces 54, 55, 56, 57, 59, 60 and 61, all of which have an arcuate outer edge and properly shaped contour to fit between the various puzzle pieces. All of these pieces are generally triangular in shape, as will be seen and these parts may be similarly colored.

In assembling the puzzle it is preferable to first insert the pointed pieces 25, 27, 29 and 30. These pieces fit together only when the piece 25 is in the notch 32, thus properly locating the other parts. If desired the pointed piece 25 may be first inserted and then the center piece 13 may be inserted which provides the proper arrangement of the pointed pieces 27, 29 and 30. Obviously if these last three pieces are inserted in improper relation, the center piece 13 can not be inserted.

Once the pointed pieces thus described are inserted together with the center piece 13, the intermediate points of the compass may be inserted. It will be noted that the piece 36 will fit only in one place in the puzzle and while the double point 37 may fit either in the notch 39 or the notch 43, the opposite end of these pieces will not fit the contour of the pieces 25 and 29. This is also true of each of the puzzle pieces 36, 45, 41 and 50. The insertion of the remaining puzzle pieces then completes the assembly of the structure.

It will be noted that when the puzzle is assembled as described the body of the puzzle may be rotated so that the puzzle piece 25 which bears the letter "N" or the word "North" is in line with the end of the pointer 22 which is attracted to the magnetic North Pole. The various puzzle pieces which extend into notches in

the frame 11 all preferably bear indicia indicating the points of the compass and are always in proper relationship when the puzzle is assembled. Thus the child may learn how to use the compass and the relationship of the various compass points. As compasses normally are of considerable interest to small children, the toy is of considerable benefit in educating the child along the lines indicated.

In accordance with the patent statutes, I have described the principles of construction and operation of my educational toy puzzle, and while I have endeavored to set forth the best embodiment thereof, I desire to have it understood that obvious changes may be made within the scope of the following claims without departing from the spirit of my invention.

I claim:

1. An educational toy including a series of puzzle pieces fitting together in a predetermined relationship, certain of said puzzle pieces being arranged about a center point and forming the points of a compass, and a compass including a support and a magnetic needle pivotally connected thereto arranged at the center point, said support forming one of said puzzle pieces and interfitting therewith.

2. An educational toy including a series of puzzle pieces capable of fitting together in a predetermined relationship, one of said puzzle pieces comprising a center piece and others of said puzzle pieces encircling said center piece and interfitting therewith in a predetermined angular relationship, said puzzle pieces forming the points of the compass, and a compass secured to said center piece centrally with respect to said puzzle points.

3. The structure described in claim 2 and in which the compass includes a casing and a magnetic needle enclosed within said casing.

4. The structure described in claim 2 and in which the compass includes a casing and a magnetic needle supported within said casing, said casing fitting in an aperture in the center puzzle piece.

5. An educational toy including a frame having a generally circular aperture therein, a series of four angularly spaced notches in the periphery of said aperture, a series of four puzzle pieces within said aperture, each puzzle piece extending into a corresponding notch and representing a compass point, and a center puzzle piece within said first named puzzle pieces and separated therefrom along an irregular line, each of said four puzzle pieces fitting said center puzzle piece in one angular relation only, and a compass positioned at the center of said circular aperture and encircled by said center puzzle piece.

6. The structure described in claim 5 and including a second series of notches in the periphery of said aperture between the first mentioned notches and four additional puzzle pieces each fitting into one of said notches and each fitting against two of said first mentioned four puzzle pieces, all of said puzzle pieces being arranged to fit together in one particular relationship.
